United States Patent Office

Des. 184,169
Patented Dec. 30, 1958

184,169

MERCHANDISE CART

Lynn Nelson Davis and Walter Herman Schray, Battle Creek, Mich., assignors to United Steel & Wire Company, Battle Creek, Mich., a corporation of Michigan

Application December 14, 1956, Serial No. 44,197

Term of patent 14 years

(Cl. D14—3)

FIG. 1

Figure 2 is a perspective view of the merchandise cart as viewed from the other side and rear thereof.

The characteristic features of the design in said merchandise cart are shown in solid lines.

What is claimed is:

The ornamental design for a merchandise cart, as shown and described.
